DESIGN FOR A GOBLET OR SIMILAR ARTICLE

Edgar Mott Bottome, Moundsville, W. Va., assignor to Fostoria Glass Company, Moundsville, W. Va., a corporation of West Virginia

Application April 10, 1937, Serial No. 68,667

Term of patent 3½ years

To all whom it may concern:

Be it known that I, Edgar Mott Bottome, a citizen of the United States of America and resident of Moundsville, county of Marshall, and State of West Virginia, have invented a new, original, and ornamental Design for a Goblet or Similar Article, of which the following is a specification, reference being had to the accompanying drawing, forming part thereof, in which—

The single figure is a side elevation of a goblet or similar article, showing my new design.

The essential feature of the invention resides in the surface ornamentation borne by the goblet, said ornamentation continuing around the entire periphery of the bowl portion of the goblet.

I claim—

The ornamental design for a goblet or similar article, substantially as shown and described.

EDGAR MOTT BOTTOOME.
